(57) **CLAIM**

The ornamental design for an electric kids motorcycle, as shown and described.

DESCRIPTION

FIG. 1 is a top, rear and right-side perspective view of an electric kids motorcycle showing my new design;

FIG. 2 is right-side elevation view thereof;

FIG. 3 is left-side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate the portions of the electric kids motorcycle that form no part of the claimed design.
